ATTORNEY

UNITED STATES PATENT OFFICE.

AMSON G. ILLCH, OF NEW YORK, N. Y.

ATTACHMENT HOOK FOR SAFETY BELTS.

Application filed April 3, 1926. Serial No. 99,472.

This invention relates to improvements in attachment hooks secured to window casings to provide a means by which a window cleaner may attach his safety belt as a precautionary measure against falling.

An object of this invention is to provide a device of the character described which may be applied to a hollow window casing.

Another object is to provide a device of the character described which may be readily secured and attached to a window casing by a minimum amount of labor; and also provide a device which may be manufactured at a minimum cost.

These objects are attained by means of the device illustrated in the accompanying drawings in which:—

Figure 1, is a top view of the device shown attached to a window casing.

Figure 2, is an elevation of the device attached to the window casing and shows a method of locking the device upon same.

Figure 3, is a detailed view which shows the method of applying the device to and upon the window casing.

Figure 4, shows a modified form attached to window casing.

Figure 5, is a sectional elevation, Figure 6, a section on line 6—6, and Figure 7, a modified form of this device.

Referring to the drawings in detail, 1, designates an attachment hook to which the window cleaner's safety belt may be secured, while 2, is a U shaped prolongation of the hook and is adapted to extend through the perforations 3 and 4 in the window casing 5. One end of the U shaped bolt is threaded as at 6, to take a lock-nut 7. To facilitate the operation of threading the device through perforations 3 and 4, the U shaped section of the device is slightly off-set as at 8; and in order to feed the device through perforation 3, in casing 5, it is necessary to hold the device in a horizontal position as shown in

Figure 3. After the main part of the U shaped section has entered the perforation 3, the device is turned at right angle so that the threaded portion 6, points downwardly to line up with the perforation 4, thus holding the device in a vertical position when finally secured. As a precautionary measure against the displacement of the nut 7, which is applied after the threaded section 6, has been passed through the perforation

4, the end of the threaded section 6, may be hammered down over the nut thus posi-

tively preventing the displacing of same. It will be noted, however, that even with the nut removed, the device will hold upon the casing and cannot be accidentally dislodged. 60

To take the pressure or strain of any weight which may be attached to the hook 1, the U shaped section 2, is formed with a projecting bearing member 9, which is pulled tightly against the casing 5, after the nut 7, is threaded upon the end 6. In place of an ordinary nut 7, an attachment member 7' may be provided, which screws over the threaded end 6, as shown by dotted lines in Figure 2, and, in place of either nut or attachment member a tap screw may be employed.

In Figure 4, there is shown a modified form of this device which engages through the casing 5, through perforations 3 and 10, and this device consists of an attachment member 1, and a bar 11, turned in a quadrant and provided with a threaded end 12, and lock-nut 13. This form of device is applied in horizontal position through adjacent sides of the casing as clearly illustrated. 75

The embodiment as shown in Figure 5, consists of complementary members 14 and 15, each of which is formed with a half head 16 and 17, respectively and with prongs 18 and 19, which are adapted to engage through perforation 20, in the casing 5. One side of the prongs 18 and 19, are curved as at 21 and 22, and the said curved surfaces roll together as the head sections are separated during the process of attaching the device to the casing, as shown by dotted lines. 90

After the prongs 18 and 19, enter the perforation in the casing, the head sections are brought together and by means of a screw 23, the beveled surfaces 24 and 25, are brought together bringing the ends of the prongs, 18 and 19, tightly against the inside of the casing 5, thus assuring rigidity to the member when attached to the casing. 100

Figure 7, shows the appearance of the device when finally set into position. To prevent accidental displacement of the screw 23, the end of same may be hammered or riveted over as at 26. 105

Various modifications may be embodied without departing from the spirit of this invention and it is not intended therefore to limit this invention to the particular embodiments shown.

What is claimed is:

In combination with a metal window cas-

ing having a hole through a wall of the casing, a support member comprising two complementary members both of which have portions which are adapted to pass through 5 the same hole and to have their ends bear against the rear side of the wall of the casing and each having a portion adapted to limit the distance such member can pass into said hole, and means for drawing said

complementary members together to contact 10 in a plane at an angle to the face of the casing so that they will bear against both the inner and outer faces of the wall of the casing.

Signed at New York, in the county of 15 New York, and State of New York, this 1st day of April, A. D. 1926.

AMSON G. ILLCH.
